UNITED STATES PATENT OFFICE

LESSING L. KOLE, OF MILWAUKEE, WISCONSIN

SPECIAL PACKAGE FOR COMPACTS

Application filed January 12, 1929. Serial No. 332,550.

The object of my invention is to provide a novel and easily opened container adapted to safely house rouge and face powder compacts for transportation; to provide a novel arrangement and means for packing the compacts to prevent breakage; and particularly to provide a container which can be manufactured at small expense; is of light weight and easily handled.

10 I attain the objects of my invention by the device illustrated in the accompanying drawings, in which,—

Figure 1 is a perspective view of the invention;

15 Fig. 2 is a longitudinal section through the container with a portion of the protective covering tube broken away to show the arrangement of the compacts and with a portion of the contents removed and the 20 interior of the structure shown in side elevation to indicate the disposition of the cord 6;

Fig. 3 is a transverse section through the container on line 3—3 of Fig. 2;

25 Fig. 4 is a transverse section of the container in open position ready to receive the compacts; and

Fig. 5 is a perspective view of the compacts and associated packing discs in spaced relation.

Like numerals designate like parts in each of the several views.

Referring to the accompanying drawings, I provide a tubular cardboard or similar 35 casing 1 consisting of two semi-cylindrical sections 2 which are hingedly connected by suitable flexible hinge strips 4, preferably of paper, as shown in Figs. 3 and 4. Positioned within the container is a suitable 40 sheet of protective soft packing such as paper pulp or cotton wadding of sufficient size to just encircle the compacts when the container is closed. The container is sealed by means of a longitudinal cord binding 45 strip 8 of stout paper disposed as shown in Figs. 1 and 2 and concealing all but the end of a cord 6. Cord 6 is fastened near one end of the container from a point 50 within the container, passing through an opening and thence across the end of the

container and along the channel left between the longitudinal free edges of the semi-cylindrical sections of the container as shown in Fig. 3 and thence over the other end of the container and partway 55 back so that a portion of its end projects beyond the paper binding strip 8 to be readily grasped for opening the container. I provide transverse strips 3 which are pasted over the two sections of the container 60 across the channel between their free edges to hold them securely in place. I then affix the strip 8. These strips preferably are paper tape strips provided with glue or gum on one of their surfaces.

I provide a novel arrangement and means for safely housing the compacts consisting in arranging the compacts in pairs with the face powder on the compacts arranged to face each other and with a thin wax paper disc 11 placed adjacent the face powder side of each of the compacts and with either a corrugated pasteboard or similar spacing ring 12 or a disc of paper pulp or cotton wadding material interposed in place of ring 12 as a spacing or shock-absorbing 75 element.

In packing the container the semi-cylindrical sections 2 are spread in open position, as shown in Fig. 4, and the series of compacts 10, protective wax paper discs 11 and resilient paper or other rings or discs 12 are positioned successively and in the arrangement shown in Figs. 2 and 5 and the element 9 is then wrapped around, as indicated in dotted lines in Fig. 4, and the semi-cylindrical sections closed to form the cylinder. The transverse strips 3 are then affixed and the longitudinal binding strip 8 is fastened in place over the cord 6 which has been brought along the channel to form the free edges of the sections as shown in Fig. 3, one end of the cord protruding to permit of its being readily grasped.

To open the package the purchaser merely grasps the free end of the cord, as shown in Fig. 2 and pulls it, thus tearing its way through the paper binding strip 8 and allowing the package to open out in the 100

manner shown in Fig. 4 when the compacts may be readily taken out.

This special package provides a safe, convenient and inexpensive container for shipping these face powder compacts, which are somewhat fragile. In the past these compacts have generally been shipped in pairs in paper glassine envelopes or in egg crates which is a very expensive and inconvenient 10 method of handling.

This new special package has proven very effective for the shipping of rouge and compacts in bulk as it holds a great quantity, eliminates breakage and is easy to 15 store. When I ship plain rouge or compacts (unimbossed) I just have wax paper or cotton separators in place of the rings 12 but when I ship rouge or compacts with a trade or other name embossed on the face 20 powder I provide cardboard packing rings 12 which function to space the compacts and to protect the embossing on the powder cakes.

What I claim is:

- 25 1. A special package for rouge and face powder compacts, comprising tubular cardboard or similar casing elements open at the end and of appropriate size to provide a narrow channel between the longitudinal 30 free edges of same, a flexible hinge element hingedly connecting the aforesaid casing elements along adjacent longitudinal edges, a cord secured to one of the casing elements near one end thereof and extending around 35 the end of the container and longitudinally in the channel above described and around the other end of the container, and a cord binding strip of paper affixed to the package and extending around both ends of the container and along one side thereof and concealing all but the ends of the cord, said 40 paper strip permitting of the package being opened by merely pulling the cord sufficiently to tear the paper strip.
- 45 2. A container for rouge and face powder compacts, comprising semi-cylindrical cardboard casings, a flexible hinge member connecting said casings along one of the longitudinal edges of each of the casings, 50 the casings being of suitable size to leave a narrow longitudinal channel between their free edges when closed, a cord anchored in one of the casings and adapted to be threaded around the container and following 55 the path of the longitudinal channel, and a paper strip extending around the container and securing the cord while at the same time concealing the container.
- 60 3. In combination with the apparatus described in claim 2, a rectangular strip of cotton wadding of suitable size to have its longitudinal free edges meet when wrapped around the compacts with the wadding in the casing, and paper projecting rings interposed between successive compacts.

4. In combination with the apparatus described in claim 1, a plurality of paper strips pasted transversely of the container to hold the sections thereof in closed relation over the compacts, and a paper binding strip extending over both ends of the container and over the longitudinal channel formed between the free edges of the semi-cylindrical casing sections.

5. In a container for rouge and face powder compacts, the combination of a strip of protective soft padding of suitable size to encircle the compacts, a pair of semi-cylindrical cardboard casings hingedly connected and of such size as to provide a narrow longitudinal channel between their free edges when closed over the padded compacts, a cord anchored in the aforesaid casing near one end thereof and approximately opposite to the aforesaid longitudinal channel, said cord being extended around the end of the container and along the longitudinal channel between the free edges of the semi-cylindrical casings, thence around the other end of the container and in a reverse direction 90 for a short distance, a paper binding strip pasted over the container and positioned to conceal the cord except at its extreme free end, and conceal the edges of the container in their nearly closed relation, the end of the cord being free to be grasped and pulled and tear the binding strip and open the container, and transverse paper strips pasted across the respective casing sections to more securely seal the package while permitting 95 of its being opened by pulling the cord.
